UNITED STATES PATENT OFFICE.

ROBERT A. HAMMOND, OF SANDWICH, MASSACHUSETTS.

WIRE ROPE OR HAWSER.

SPECIFICATION forming part of Letters Patent No. 608,673, dated August 9, 1898.

Application filed October 7, 1897. Serial No. 654,428. (No model.)

To all whom it may concern:

Be it known that I, ROBERT A. HAMMOND, a citizen of the United States, residing at Sandwich, in the county of Barnstable and 5 State of Massachusetts, have invented an Improvement in Wire Ropes or Hawsers, of which the following is a full, clear, and exact description, reference being had to the accompanying drawings, making part of this 10 specification, in which—

Figure 1 is a view of a piece of wire rope embodying my invention, one end being un-twisted to better illustrate the construction and arrangement of parts. Fig. 2 is an enlarged transverse section on the line 2 2 of 15 Fig. 1.

My invention has for its object to improve the construction of wire rope, whereby it is rendered more flexible, durable, and convenient to handle than heretofore; and to this end my invention consists in a rope formed of a series of wire strands laid or twisted together, each strand being composed of a series of wires twisted tightly together and 25 said strands being each covered with a twisted strand of hemp or other fibrous material which is "served" around the same to form an outer elastic covering therefor, a suitable number of strands so formed being afterward 30 twisted together, with or without a core, to form a rope or hawser, as hereinafter more fully described.

In the said drawings, A represents a piece of wire rope or hawser, which is composed of 35 any suitable number of strands b—in the present case six—which are laid or twisted together, as shown, around a core c, which I prefer to employ when the rope is composed of an even number of strands; but this core 40 may be dispensed with, if desired. Each of the strands b is composed of a plurality of wires d, which are twisted tightly together, after which the wire strand so formed is firmly and closely wound or wrapped in one 45 direction by "serving" it with a single twisted strand e, of hemp or other suitable fibrous material, preferably tarred to prevent rust or corrosion, which thus forms a soft and elastic outer covering or cushion for the said 50 wire strand and also serves to protect the wires from wear. In practice the twisted strand of hemp is served around the group

of wires in the same machine in which said wires are twisted together, the hemp wrapping being applied to the outside of said 55 group of wires as they are being twisted.

The nautical difference between serving and the ordinary spiral twisting of the hemp covering-strands is very great, since the strands of a served covering will lie close 60 together almost transversely of the wire strands, as shown at e, Fig. 1, and when the rope is bent the coils of serving will not open and admit water, while a spirally-twisted covering will stretch and open as the rope is 65 bent, thus exposing the wires beneath to the action of water. In the operation of serving the hemp covering strands or coils are tightly compressed or jammed one against the other, and thus when the rope is bent the coils of 70 serving will expand on the outer side of the curve in the direction of their diameters, leaving no chance for the water to enter, and on the inner side of the curve the coils will be jammed together even tighter than when 75 first wound, making the rope more resilient, which is another advantage. Still another point is that the serving being freshly tarred when put on the tar will exude and form a coating on the wires under the serving, and 80 thus additionally protect them. By doing away with hempen cores in the wire strands b I can put one more strand b in a rope without increasing its diameter and greatly increasing its strength for a given diameter 85 over a rope having hempen cores.

By firmly and closely winding each group or series of wires which form a strand with hemp or other fibrous material, as above described, the friction or rubbing of the wires 90 of one strand against those of another, as is the case in all wire rope hitherto constructed, is entirely avoided, while the individual wires are also prevented from rubbing against the covering and wearing the same, thus greatly 95 increasing the durability and life of the rope. Furthermore, the outer fibrous wrapping of each of the strands b forms an elastic cushion covering, which renders a rope or hawser composed of such strands exceedingly flexible 100 and resilient, and as no wires are exposed on the outside of the rope it may be safely handled without injury to the hands from slivers or splinters from the wire, which forms a se-

rious objection to the use of wire rope as hitherto constructed.

Wire rope constructed as above described is particularly well adapted for use for ships' rigging, hoisting-rope, towing-hawsers, &c., for the reason that it will not become corroded by exposure to the weather or salt water.

What I claim as my invention, and desire to secure by Letters Patent, is—

- 10 1. A wire rope or hawser, composed of a series of wire strands laid or twisted together, each strand being composed of a plurality of wires twisted tightly together, and said wire strands being each provided with a twisted strand of hemp or other fibrous material "served" around the same in substantially transverse coils to form an outer elastic covering or cushion therefor, substantially as de-
- 15
- 20

2. The combination in a wire rope or hawser, of a series of wire strands laid or twisted together, each strand being composed of a plurality of wires twisted tightly together in direct contact with each other, and said wire strands being each provided with an outside wrapping composed of a twisted strand of tarred hemp or other fibrous material "served" spirally around the same in substantially transverse coils to form an elastic covering or cushion which also forms the outer surface of the rope or hawser, substantially as described.

Witness my hand this 6th day of October, A. D. 1897.

ROBERT A. HAMMOND.
